UNITED STATES PATENT OFFICE.

ALBERT W. ENGEL, OF CHICAGO, ILLINOIS.

COUNTER DISPLAY BOX.

Application filed August 10, 1925. Serial No. 49,274.

The purpose of this invention is to provide a receptacle in the nature of a folded paper box adapted to serve as a shipping carton for merchandise, and also arranged to be used on the store counter as a dispenser for the goods and as a display device for advertising them. It consists of certain features and elements of construction as herein shown and described, and as indicated by the claims.

10 In the drawings:

Figure 1 is a plan view of a blank for a box embodying this invention.

15 Figure 2 is a plan view of a supplemental blank for the box.

Figure 3 is a perspective view showing the front and side of the box with the cover in raised position giving access to the contents and serving as a display area for advertising matter.

20 Figure 4 is a side elevation with parts broken away.

Figure 5 is a rear elevation of the box in closed position.

Referring first to Figure 1, the front wall 25 of the box is identified in the blank at 1 with a bottom wall, 2, and a top or cover, 3, extending in alignment therefrom. The side walls of the box are made of double thickness, and the inner laminæ are shown at 4—4 30 extending laterally from the blank of the bottom, 2. The back wall, 5, is also attached to the bottom, 2, for folding upwardly therefrom.

Figure 2 shows a supplemental blank in 35 the form of a strip which includes a duplicate front wall, 6, and duplicate side walls, 7—7 with locking tabs, 8, extending from said side walls for folding around the back wall, 5, to be engaged in the slotted openings, 9, formed 40 therein. The tabs, 8, and intermembering openings of the back wall, 5, are more fully described and claimed in my co-pending application Serial Number 593,273 filed Oct. 9, 1922.

45 When the two blanks are assembled, the front wall, 6, is placed inside the wall, 1, but the duplicate side walls, 7—7, are lapped outside of the corresponding side walls, 4—4, thus providing two separated laminæ at each side 50 of the box, between which are fitted the lateral flaps, 10, extending from the cover, 3. These flaps, 10, are notched at 11 for engaging the upper edges of the side walls, as shown in Figures 3 and 4 holding the cover in up- 55 raised and preferably oblique position. For

limiting this opening position of the cover the inner side walls, 4, are formed with curved and upwardly trending slits, 12, and the flaps, 10, are provided with stop lugs, 13, in said slits so as to arrest the opening movement of 60 the cover as the lugs reach the upper ends of the slit as shown in Figure 4. When thus opened, the box may be placed on the counter with the front wall, 1, and cover, 3, facing the customer, and preferably provided with 65 advertising matter describing the goods, while the goods themselves contained in the box are readily accessible from behind the counter.

In order that the box may serve as a ship- 70 ping carton I provide a flap, 14, attached to the cover, 3, at the side opposite the edge which is hinged to the front wall, 1, and this flap is formed with laterally pointing triangular flaps, 15, so that when the cover is closed 75 and the flap, 14, is folded down against the back wall of the box, these tabs, 15, may be lapped under similar but oppositely pointing tabs, 16, which are associated with the tabs, 8, 80 on the supplemental blank. This holds the 80 cover securely in closed position.

When the cover is raised to the position 85 shown in Figure 3 the flap, 14, may be turned upwardly into a substantially vertical plane, and its upwardly presented surface may also serve to display advertising matter. Preferably for holding it upright I attach a strip, 17, of soft tin or like metal to the under surface of the cover, 3, as by means of a piece 90 of gummed paper indicated at 18, and the projecting portion of the strip, 17, may be bent upwardly back of the flap, 14, as shown in Figure 4.

I claim:—

1. A folded box including side walls and 95 a front wall with a top or cover hinged to the latter, and lateral flaps on said cover lapping the side walls, the side walls having upwardly trending slits which stop short of their upper edges and the cover flaps having lugs engaged in said slits for limiting the 100 upwardly swinging movement of the cover.

2. A folded box including side walls and 105 a front wall with a top or cover hinged to the latter, and lateral flaps on said cover lapping the side walls, the side walls each comprising two separated laminæ and the cover flaps extending between said laminæ, the inner member of each side wall having an upwardly trending slit stopping short of the upper edge 110

of the wall and the cover flap having a stop lug extending into the slit for limiting the upward swing of the cover.

3. A folded box construction comprising a blank which includes top having flap portions extending from opposite edges and bottom walls, front and back walls and side walls and the second blank which includes a duplicate front wall, duplicate side walls hinged there-
10 to and tabs extending from the side walls for interlocking engagement with the back wall of the first blank, said second blank being assembled with its duplicate front wall inside the front wall of the first blank and with its side walls overlapping outside the sides of the first blank and said flaps of the cover being interposed between the respective side walls of said blanks.
15

4. A folded box including side walls and a front wall with a top or cover hinged to the latter, and lateral flaps formed to rest on the upper edges of the side walls to hold the cover in up-raised position, said side walls having upwardly-trending slits stopping short of their upper edges and the cover flaps 25 having lugs engaged in said slits for limiting the opening movement of the cover.

5. In the combination defined in claim 1, said slits in the side walls being arcuately formed about a center in alignment with the hinged connection of the cover, whereby said lugs may be maintained in sliding guidance in the slits in all permissible positions of the cover.

ALBERT W. ENGEL.
